(57) **CLAIM**

The ornamental design for a transformable toy, as shown and described.

DESCRIPTION

FIG. 1 is a front view of the binocular form for a transformable toy;

FIG. 2 is a rear view of the binocular form thereof;

FIG. 3 is a right side view of the binocular form thereof;

FIG. 4 is a left side view of the binocular form thereof;

FIG. 5 is a top view of the binocular form thereof;

FIG. 6 is a bottom view of the binocular form thereof;

FIG. 7 is first perspective view of the binocular form thereof;

FIG. 8 is second perspective view of the binocular form thereof;

FIG. 9 is third perspective view of the binocular form thereof;

FIG. 10 is a front view of the sword form thereof;

FIG. 11 is a rear view of the sword form thereof;

FIG. 12 is a right side view of the sword form thereof;

FIG. 13 is a left side view of the sword form thereof;

FIG. 14 is a top view of the sword form thereof;

FIG. 15 is a bottom view of the sword form thereof;

FIG. 16 is a perspective view of the sword form thereof; and,

FIG. 17 is another perspective view of the sword form thereof.

The broken lines in the drawing are for illustrative purposes only and form no part of the claimed design.

The transformable toy can reversibly change into a binocular and sword forms.
